SHEET OF METAL OR MATERIAL

Application filed December 20, 1928, Serial No. 327,411, and in Great Britain December 10, 1927.

This invention consists of an improved sheet of metal or material used in the manufacture of articles. According to this invention a sheet of metal or material, herein-after referred to as the sheet, is, before being employed in a press or like machine for the purpose of manufacturing blanks or articles therefrom, provided with two irregularly-shaped marginal-edges which are formed so as to have several cut-out-parts each conforming or approximately conforming in shape to either a half or to a greater or lesser part of the profile of whatever size of blank is afterwards, progressively and preferably 10 in rows, cut or punched out of such sheet during the manufacture or of any stage in producing blanks or articles therefrom. Each irregularly-shaped marginal-edge of the said sheet is remote one from the other and the cut-out-parts are arranged therein at such a pitch-distance apart as to allow the said sheet to be fed into, through and out of a press or like machine, equipped with one or more rows of suitably-formed punch and die-tools 20 without the risk of half-blanks, part-blanks or any sheared or cut-off parts may get into the die-tools. In known methods it is necessary that the operation be continually interrupted so as to remove these half-blanks or part-blanks, otherwise the die-tools would become choked, broken, or chipped as the result of the side stresses imposed thereon or of the wedging of such half-blanks or part-blanks therein; therefore the provision of 25 an improved sheet of metal or material which has been previously adapted and prepared as disclosed in this invention is of great practical utility particularly as its use ensures that the constant feeding of such adapted and prepared sheets is maintained in a follow-on manner and in rapid succession and with one irregularly-shaped marginal-edge of one sheet contiguous with another irregularly- 35 shaped marginal-edge of any other of my

adapted and prepared sheets following it into and through the said press or like machine.

In the known methods of producing articles such as pen nibs or nails folded from sheet-metal blanks, or plain blanks, it has not been possible, without stopping the press or like machine and feeding the sheet by hand, to produce such articles without the punches and dies in the press or like machine cutting half-blanks or part-blanks firstly 50 from that marginal-edge which first enters into, and secondly from that marginal-edge of the said sheet remote therefrom as it leaves or passes out of the cutting position of the punches and dies employed in the said press, 55 and it is to overcome the cutting of such half-blanks or part-blanks that the present invention has been devised.

An object of this invention is to provide a sheet of metal or material which is adapted 65 and prepared previous to its being used to manufacture blanks or articles therefrom with two irregularly-shaped marginal-edges, each such marginal-edge being remote one from the other on the said sheet and so 70 formed as to have several cut-out-parts each conforming or approximately conforming in shape and size to either one half, or to a greater or lesser part of the profile or contour of whatever particular form of blank 75 it is intended to subsequently cut or punch out of such adapted and prepared sheet so that half-blanks or part-blanks cannot result as is ordinarily the case when known methods are employed. 80

Another object of this invention is to provide sheets of metal or material previously adapted or prepared in the manner disclosed herein which enable the continuous and uninterrupted feeding thereof into and through 85 a press or like machine provided with suitable dies and punches to be accomplished without stopping the said press or like machine.

The invention will now be described with 90

reference to the accompanying drawings, in which:—

Figure 1 is a view showing two end parts of a plain sheet of metal adapted and prepared according to this invention and before blanks or articles are produced therefrom.

Figure 2 is a view showing similar end parts of an adapted and prepared sheet of the kind shown in Figure 1 after it has had blanks or articles cut out therefrom.

Figure 3 is a view showing four corner parts of an adapted and prepared sheet after it has been fed through a press or like machine and had pen-nib blanks removed therefrom.

Figure 4 is a view showing four corner parts of an adapted and prepared sheet before it has been fed through a press or like machine to have chain-link blanks, indicated by dotted lines, removed therefrom.

Like letters of reference refer to like parts throughout the drawings.

A plain or imperforated sheet of metal or material A, before it is fed into a press or like machine for the purpose of having blanks or articles produced therefrom, is so cut or formed on two of its marginal edges a, each remote one from the other, as to produce marginal-edges a of irregular shape which are produced during the forming of the cut-out-parts b, this essential condition being brought about by adapting and preparing a sheet of metal or material according to this invention. These cut-out-parts b are correctly spaced and arranged at a correct pitch-distance apart, both longitudinally and transversely of the said sheet, to suit the size, location and pitch-distance of whatever blanks are subsequently to be cut from such sheet; the said cut-out parts b are also each of such shape as to conform or approximately conform to either one half or to a part of the contour of each blank hole B or of each blank or article (not shown) which it is intended to subsequently produce from such sheet of metal or material.

In operation an adapted and prepared sheet provided according to this invention with its cut-out-parts b therein is fed into and away from the operative cutting movement of the punches and dies in a press or like machine. One side of the said punches passes into and nearly touches or actually rubs, but without cutting, the first engaged edges of the cut-out-parts b of the said sheet and the other side of the said punches passes into and nearly touches or actually rubs, but without cutting, the last engaged edges of the other cut-out-parts b of the said sheet, therefore the so-called pitch-distance between these reversely arranged cut-out-parts b or of the said two reversely arranged irregularly-shaped marginal edges a is always so arranged as to suit the size of the sheet and

the shape of the blanks subsequently to be cut from the said sheet, and therefore the feeding of the said sheet into and through a press or like machine is so arranged or set as to suit that pitch-distance necessary to bring the cut-out parts b located in the irregularly-shaped marginal-edge a of the sheet finally passing out from the cutting action of the punches in the correct position or location for the said punches to correctly register therewith and enter therein.

It will be obvious that the irregularly-shaped marginal-edges a with their cut-out-parts b can be produced by several known methods; but preferably the ends of a plain sheet are brought under the action of suitably-shaped shear-blades or suitably-shaped notching or cutting tools mounted in a shearing machine, guillotine, press or like machine and given the aforesaid correctly formed irregularly-shaped marginal-edges a and cut-out-parts b. It is to be observed that this can only be successfully accomplished or economically performed by separate die-tools and punches, shear-blades or notching-devices other than those which serve to produce the finished blanks or articles from the said adapted and prepared sheet of metal or material.

All sheets of metal or material embodying the cut-out-parts b, hereinbefore referred to, have two marginal edges at the so-called sides of such sheet which are either left plain or are provided with holes, notches, slits or the like of any known form to serve as means for enabling the said sheet to be impelled or fed into and through a press or like machine and also for locating the said sheet therein during blanking.

The edges of the cut-out-parts b which correspond or approximately correspond in shape to that part of the contour of the hereinbefore referred to blank-holes B are in each case formed in my adapted and prepared sheet at a like pitch-distance apart in relation one to the other.

I claim:—

1. Sheet material prepared for use in a blanking press from which parts of the leading edge of the sheet have been cut out to the contour of part of one side of a blank to be cut from the sheet, and parts of the trailing edge of the sheet have been cut out to the contour of part of the opposite side of a blank.

2. Sheet material prepared for use in a blanking press from which parts of the leading edge of the sheet have been cut out to the contour of part of one side of a blank to be cut from the sheet, and parts of the trailing edge of the sheet have been cut out to the contour of part of the opposite side of a blank, the parts of each edge of the sheet thus cut being spaced apart at distances along that edge corresponding to the spacing

of blanking dies to the operation whereof the prepared sheet is to be subjected.

3. Sheet material prepared for use in a blanking press from which parts of the leading edge of the sheet have been cut out to the contour of part of one side of a blank to be cut from the sheet, and parts of the trailing edge of the sheet have been cut out to the contour of part of the opposite side of a blank, the parts cut in one edge being spaced from parts cut in the other edge by a multiple of the pitch distance of the blanking faces of the die by which blanks are to be cut from the sheet.
